Primary Examiner — Cynthia M Chin*(74) Attorney, Agent, or Firm* — Kolisch Hartwell, P.C.(57) **CLAIM**

The ornamental design for a skateboard, as shown and described.

DESCRIPTION

FIG. 1 is an upper, front, and right side perspective view of a skateboard showing the new design;

FIG. 2 is an upper, front, and left side perspective view thereof;

FIG. 3 is an upper, rear, and left side perspective view thereof;

FIG. 4 is a top plan view thereof;

FIG. 5 is a bottom plan view thereof;

FIG. 6 is a front elevational view thereof, where the rear elevational view is a mirror image of the front elevational view;

FIG. 7 is a right side elevational view thereof; and,

FIG. 8 is a left side elevational view thereof.

The broken lines are for the purpose of illustrating portions of the article that form no part of the claim.
